UNITED STATES PATENT OFFICE

2,476,926

PAINT LINER MACHINE

James L. Stocks, Seattle, Wash.

Application May 15, 1946, Serial No. 669,827

5 Claims. (Cl. 91—12)

1

The invention relates to a marker machine and more especially to a surface marker apparatus.

The primary object of the invention is the provision of an apparatus of this character, wherein a surface can be marked with a line or stripe, either continuously or intermittently, through the use of a wheeled vehicle or carriage, the apparatus being of novel construction, and is unique in the assembly of its parts, and is such that straight, curved or spiral markings can be had upon a surface.

Another object of the invention is the provision of an apparatus of this character, wherein the straight line marking is aided by a guide tape, which is wound upon a reel upon the carriage or wheeled vehicle and directs the straight line course of the latter during the marking operation.

A further object of the invention is the provision of an apparatus of this character, wherein the marking paint is manually controlled in the feed thereof, and it can be evenly distributed over the marker brush.

A still further object of the invention is the provision of an apparatus of this character, which is simple in construction, thoroughly reliable and efficient in operation, strong, durable, readily and easily handled, self guided in making straight lines, possessed of few parts, thus economical in repairs and replacements, compact and inexpensive to manufacture.

With these and other objects in view the invention consists in the features of construction, combination and arrangement of parts as will be hereinafter more fully described, illustrated in the accompanying drawings, which disclose the preferred embodiment of the invention, and pointed out in the claims hereunto appended.

In the accompanying drawings:

Figure 1 is a side view of the apparatus constructed in accordance with the invention;

Figure 2 is a front elevation thereof;

Figure 3 is a top plan view;

Figure 4 is a fragmentary sectional view taken on the line 4—4 of Figure 3 looking in the direction of the arrows;

Figure 5 is a perspective view of the flow control valve.

Similar reference characters indicate corresponding parts throughout the several views in the drawings.

Referring to the drawings in detail, the apparatus constituting the present invention, comprises a wheeled vehicle or carriage, which involves a substantially triangular shaped main

2

chassis frame 10, the wider end thereof is fore and the narrower end aft of the vehicle or carriage. Above the frame 10 is a second substantially rectangular shaped frame 11, which is supported forwardly thereof by uprights 12 rising from the main frame 10, while rearwardly such frame 11 is joined with a vertical rack 13, in which is located a vertically adjustable liquid paint receptacle or hopper 14, the front of the frame 10 being fitted with swiveled front caster wheels 15, and rearwardly by a single rear caster wheel 16. This rear caster wheel 16 is carried on a vertically swingable rocker 17, having central horizontal bearing at 18 beneath the frame 10, and regulated by a set screw 19 fitting the latter, so that the aft portion of such frame 10 can be raised or lowered. The rocker 17 is manually regulated by a hand lever 20 having linkage at 21 therewith. The lever 20 is pivoted at 22 upon a stand post 23. This post 23 rises from the frame 10 above the frame 11.

The frame 11 is disposed at the longitudinal central axis of the frame 10, and the post 23 is unitary with both, having near its upper end a laterally extended hollow handle bar 24, through which is trained an electric current supply line 25, to an electric power motor 26 supported on the frame 10, the line being equipped with an on and off electric switch 27 manually operated.

Fore of the post 23 is a reel 28, adapted for the winding thereon and unwinding therefrom of a guide tape 29, which at its outermost end is equipped with an anchoring member, such for example as a suction cup 30, that it may be attached at a selected point on a surface to be marked, a portion of this surface being indicated generally at 31. The reel 28 rotates on a horizontal axis 32 within the frame 11 above the frame 10.

The tape 29 is trained over a peripherally grooved guide roller 33, which is horizontally journaled at 34 in a carrier fork 35 therefor, which is located aft of the location of the front wheels and midway there between.

The motor 26 drives the reel 28 through a pulley and belt train 36, it being tightened and slackened by a tightener 37, which is manually controlled from a hand lever 38 on the post 23.

Built at the discharge throat end 39 of the receptacle or hopper 14 with the rack 13 is a cut-off valve 40 which is opened and closed by linkage 41 to a regulating wheel 42 carried by the post 23, and hand operated.

Within a capping guard 43 formed with the

55

rack 13 is a rotary paint brush 44, its horizontal axle 45 being suitably journaled in the guard so that the brush is located directly beneath the valve 40 aft of the apparatus.

Within the guard 43 is mounted an adjustable wiper 46 for evenly distributing paint delivered through the valve 40 when open onto the brush 44, the wiper 46 being regulated by an adjusting screw 47 exposed outside of such guard, and manually operated. The brush 44 is driven or powered through pulley and belt connections 48 and 49 respectively from the motor 26 as will be apparent from Figure 1 of the drawings.

In the painting of straight markings on a surface, the tape is let off of the reel with the outer end of such tape fastened to the surface, by the member 30, the power to the reel being cut off through slackening of the train 36 between it and the motor, and the vehicle or carriage is moved to the point where the marking is to start, the paint delivery being at this time cut off, and the brush elevated from the surface, whereupon the apparatus is now ready for marking, its travel being reversed with the tape 29 guiding it in a straight course directed thereby, as such tape is wound on the reel 28 under the driving power of the motor 26 resultant from the forced winding of the tape upon the reel.

Power for propelling the vehicle is supplied from the electric motor 26, and the apparatus is propelled both by pulling and pushing. The electric motor winds up the tape 29 on the reel 28, thus serving to pull the apparatus along, since one end of the tape 29 is fixed to the ground by means of the suction cup 30. But the apparatus is also pushed along by the electric motor 26, since the brush 44 is power driven from this motor and is in contact with the ground during the marking operation. Since one end of the tape is fixed at 30, and reel 28 and brush 44 are aligned, it is evident that as the vehicle moves along, it is constrained to move in a straight line. The brush 44 having been brought into contact with the surface to be marked from the starting point before mentioned, causes the straight line marking of this surface as the apparatus is advanced, the reel and brush being concurrently powered from the said motor under this working condition.

Now if spiral or circular marking by the apparatus is to be had, then the tape is fully wound on the reel, and the latter is passive, with the power thereto cut off, so that the apparatus can be guided by hand for those markings, as the casters permit this to be done.

What is claimed is:

1. An apparatus of the kind described, comprising a wheeled vehicle having swiveled caster wheels fore and aft thereof, a tape reel on the vehicle, a guide tape carried by the reel for winding on and from the same, a marking brush aft of the vehicle, a power unit on the vehicle for driving the brush and reel, marking fluid supply on the vehicle for delivery to the brush, and means for regulating the supply to the brush.

2. An apparatus of the kind described, com-

prising a wheeled vehicle having swiveled caster wheels fore and aft thereof, a tape reel on the vehicle, a guide tape carried by the reel for winding on and from the same, a marking brush aft of the vehicle, a power unit on the vehicle for driving the brush and reel, marking fluid supply on the vehicle for delivery to the brush, means for regulating the supply to the brush, and anchoring means carried at the outer end of the guide tape for attachment to a surface.

3. An apparatus of the kind described, comprising a wheeled vehicle having swiveled caster wheels fore and aft thereof, a tape reel on the vehicle, a guide tape carried by the reel for winding on and from the same, a marking brush aft of the vehicle, a power unit on the vehicle for driving the brush and reel, marking fluid supply on the vehicle for delivery to the brush, means for regulating the supply to the brush, anchoring means carried at the outer end of the guide tape for attachment to a surface, and means for raising and lowering the aft caster wheel to regulate contact of the brush with a surface to be marked thereby.

4. An apparatus of the kind described, comprising a wheeled vehicle having swiveled caster wheels fore and aft thereof, a tape reel on the vehicle, a guide tape carried by the reel for winding on and from the same, a marking brush aft of the vehicle, a power unit on the vehicle for driving the brush and reel, marking fluid supply on the vehicle for delivery to the brush, means for regulating the supply to the brush, anchoring means carried at the outer end of the guide tape for attachment to a surface, and means for raising and lowering the aft caster wheel to regulate contact of the brush with a surface to be marked thereby.

5. An apparatus of the kind described, comprising a wheeled vehicle having swiveled caster wheels fore and aft thereof, a tape reel on the vehicle, a guide tape carried by the reel for winding on and from the same, a marking brush aft of the vehicle, a power unit on the vehicle for driving the brush and reel, marking fluid supply on the vehicle for delivery to the brush, means for regulating the supply to the brush, anchoring means carried at the outer end of the guide tape for attachment to a surface, means for raising and lowering the aft caster wheel to regulate contact of the brush with a surface to be marked thereby, a wiper for the brush, and means for regulating power to the reel.
